UNITED STATES PATENT OFFICE.

ROBERT R. HILL AND CHARLES E. ROBINSON, OF HOUSTON, TEXAS.

DESIGN FOR A SAFETY-FIRST SIGN.

47,849.

Specification for Design.

Patented Sept. 21, 1915.

Application filed February 23, 1915. Serial No. 10,145. Term of patent 3½ years.

• all whom it may concern:

Be it known that we, ROBERT R. HILL and CHARLES E. ROBINSON, citizens of the United States, residing at Houston, in the county of Harris and State of Texas, have invented a new, original, and ornamental Design for a Safety-First Sign, of which the following is a specification, reference being had to the accompanying drawing, forming a part thereof.

The figure is a plan view of a safety first sign, showing our new design.

We claim:

The ornamental design for a safety first sign, as shown.

ROBERT R. HILL.

CHARLES E. ROBINSON.

Witnesses:

F. A. LIDDELL,
W. H. HAIRSTON.
